DESIGN FOR A CASING FOR BOILERS OR FURNACES

Henry J. Sandlas, Jr., Baltimore, Md., assignor
to May Oil Burner Corporation, a corporation
of Maryland

Application April 25, 1935, Serial No. 56,555

Term of patent 7 years

To all whom it may concern:

Be it known, that I, Henry J. Sandlas, Jr., a citizen of the United States and residing in the city of Baltimore, in the State of Maryland, have invented a new, original, and ornamental Design for Casings for Boilers or Furnaces, of which the following is a specification, reference being had to the accompanying drawing, forming a part thereof.

Figure 1 is a front view of the casing showing my new design.

Figure 2 is an end view of the casing shown in Figure 1.

Figure 3 is a rear quartering view in perspective showing the other end of the casing shown in Figures 1 and 2.

I claim:

The ornamental design for a casing for boilers or furnaces substantially as shown.

In testimony whereof, I affix my signature.

HENRY J. SANDLAS, JR.
